UNITED STATES PATENT OFFICE.

ALBERT E. COVELL, OF WEST MEDFORD, MASSACHUSETTS.

LENS-MARKING MACHINE.

Application filed February 7, 1922. Serial No. 534,819.

To all whom it may concern:

Be it known that I, ALBERT E. COVELL, a citizen of the United States, residing at West Medford, in the county of Middlesex and State of Massachusetts, have invented certain new and useful Improvements in Lens-Marking Machines, of which the following is a specification.

The invention relates to machines for use in marking lenses preparatory to trimming them, grinding their edges, and mounting them in a frame or nose piece.

After the faces of the lens have been ground, the optical center is next found and marked, this operation being performed with apparatus now commonly used by opticians. At this time, also, the axis of the lens, if it has a cylindrical grinding, is determined and marked. If the lens is to be de-centered it is placed on a lens marking chart having a multiplicity of lines designed to assist the optician in determining the degree of decentration and marking the geometrical center of the lens. These lines also assist the optician in marking the horizontal axis, and if desired, also, the vertical axis of the lens, so as to assist him in placing the lens properly in the edge grinding machine and in locating the lens accurately in the frame or nose piece.

The lens marking charts above referred to contain such a multitude of lines, in order to adapt them for use under a great variety of conditions, that they are very confusing and great care is required on the part of the optician to avoid making errors in performing the marking operation, particularly if the lens has a complicated grinding. It is the chief object of the present invention, therefore, to devise a machine or apparatus in which this marking operation can be performed with greater accuracy and facility, in which the liability of making errors will be substantially eliminated, and which can be adjusted quickly to practically any set of conditions.

The nature of the invention will be readily understood from the following description when read in connection with the accompanying drawings, and the novel features will be particularly pointed out in the appended claims.

Referring now to the drawings,

Figure 1 is a plan view of a machine embodying the invention in the form at present preferred;

Fig. 2 is a plan view of the gearing used in the machine;

Fig. 3 is a central cross sectional view of the machine shown in Fig. 1; 60

Fig. 4 is a plan view of a lens ready to be marked in this machine; and

Fig. 5 is a plan view showing certain steps of the marking operation.

The machine shown comprises a central 65 disk 2 of circular outline having two geometrical axes thereon at right angles to each other, as indicated at 3 and 4. At one side of the axis 4 is a series of lines 5, preferably spaced apart by intervals of one mm., and 70 forming a scale to assist the workman in determining the proper degree of decentration. Consequently, this scale may be referred to as a decentering scale. The disk 2 is secured to the upper face of a part 6 75 which rotates on a pin or stub shaft 7 secured fast in a base plate 8. This member 6 forms, in effect, a hub for a pinion 9 which is secured to said member.

Encircling the disk 2 is an annular disk 80 10 having a line 12 extending diametrically thereacross and designed to designate the location of the axis of the cylindrical grinding of the lens. This disk preferably is mounted in the same plane with the disk 2, 85 and it is secured fast to the upper surface of an annular plate 14 which is mounted on a reduced part of the hub 6 and is guided thereon, as clearly shown in Fig. 3. An annular gear 15 is secured to the lower face 90 of the plate 14 in any convenient manner. The annular plate 14 fits snugly within another annular member 16 which is secured to the base plate 8 by spacing studs or rivets. Mounted on certain of these studs are gears 95 17 and 18, respectively, which mesh with the respective gears 9 and 15, the margins of the gears 17 and 18 projecting beyond the base 8 so that they may be conveniently manipulated by the workman. A spring plate 100 19 bears against the face of the gear 17 and serves to exert a frictional drag on it and thus tends to maintain it, and the central disk, in their adjusted positions. There is sufficient friction on the annular plate 14 105 to keep the disk 10 from turning accidentally.

A circular scale 20, graduated in degrees, encircles the annular disk 10 and serves to indicate the angular position of the line 12. 110 This scale is supported on the upper surface of the part 16. The disks 2 and 10 and

- the scale 20 are all covered and protected by a transparent face plate 21, preferably made of glass or celluloid, and having vertical and horizontal axes 22 and 23 marked thereon. This face plate is held in place by a marginal ring 24 and screws 25 which extend through the ring and are threaded into the plate 16. The edges of the ring 24, base plate 8, and the intermediate stationary parts are substantially flush with each other, with the gears 17 and 18 projecting beyond the marginal edges of these parts so that they may be conveniently manipulated by the workman's fingers.
- 15 For the purpose of explaining the use of the machine let it be assumed that a lens L, Fig. 4, has both spherical and cylindrical grindings and that it is to be set in a frame decentered to the right four mm., and with the axis at 45° . The optical center C, Fig. 4, is first found and marked by an ink dot; and at this time, also, the axis of the cylindrical grinding is determined and designated by dots A and B. The workman next sets the central disk 2 with the decentering scale 5 at the right, as shown in Fig. 5, (since the lens is to be decentered to the right) and he adjusts the annular disk 10 to bring the line 12 into the 45° position, as shown in Figs. 1 and 5. He then places the lens L on the machine with the optical center C superposed on the center of the central disk 2, and the axis or line A—B superposed on the line 12. With the parts in this position he makes dots or marks D and E on the lens at points superposed on the horizontal axis 23 to designate the horizontal geometrical axis of the lens. While he holds these marks D and E on the axis 23 he moves the lens L to the right four mm., thus moving the optical center C to the position shown in Fig. 5. The axis A—B is now offset with reference to the line 12 but is parallel thereto. The workman now makes a mark or dot at F, Fig. 5, immediately over the center of the central disk 2, and this dot F will be used as the geometrical center of the lens in trimming it and grinding its edge to the desired outline. If desired, marks may also be made at this time at G and H at points above the line 22 to indicate the vertical geometrical axis of the lens. The markings of these geometrical axes and of the geometrical center F not only are useful in guiding the workman in cutting the lens to the required shape and grinding its edge, but they are equally valuable as guides in properly locating the lens in the frame or nose piece.
- 60 If the lens were to be decentered downwardly the scale 5 would be located below the axis 4, as shown in Fig. 1, and instead of guiding the lens on the horizontal axis 23 in moving it to its decentered position, it would be guided on the vertical axis 22.

In other words, the central disk 2 is adjusted with the scale in the direction in which the lens is to be decentered and the axes 22 and 23 are subsequently used, both to guide the operator in moving the lens to its decentered position, and also in marking the geometrical axes on the lens. The line 12 on the annular disk is always adjusted to the angular position of the axis prescribed for the cylindrical grinding of the lens.

75 It will now be appreciated that the machine can be set very quickly to agree both with the direction of decentration and also the position of the axis of the cylinder. The workman can tell at a glance whether the machine is set to agree with the prescription, and he can then mark his lens without being confused by lines additional to those that he needs in performing the marking operation. The marking operation, therefore, is facilitated and the liability of making errors is substantially eliminated.

80 While I have herein shown and described the best embodiment of the invention of which I am at present aware, it will readily be understood that the invention may be embodied in other forms without departing from the spirit or scope of the invention.

85 Having thus described my invention, what I desire to claim as new is:

90 1. A lens marking machine comprising, in combination, a central disk having a scale thereon, a second disk adjustable about the center of said central disk and having means thereon to designate an axis, a transparent plate covering said disks and having two geometrical axes thereon at right angles to each other, and a scale cooperating with said second disk.

95 2. A lens marking machine comprising, in combination, a central disk having a decentering scale thereon, a second disk adjustable about the center of said central disk and having means thereon to designate an axis, said disks being relatively adjustable about the center of the central disk, a transparent plate covering said disks and having two geometrical axes thereon at right angles to each other, and a scale cooperating with said second disk to indicate its angular position.

100 3. A lens marking machine comprising in combination, a central disk having a decentering scale thereon, a second disk adjustable about the center of said central disk and having means thereon to designate an axis, said disks being relatively adjustable about the center of the central disk, a transparent plate covering said disks and having two geometrical axes thereon at right angles to each other, a scale cooperating with said second disk to indicate its angular position, and means for adjusting said disks about said center independently of each other.

105 4. A lens marking machine comprising,

- in combination, a central disk having a decentering scale thereon and also having thereon two geometrical axes at right angles to each other, a second disk of substantially 5 greater diameter than the first disk and having a line located diametrically thereon to designate an axis, said disks being relatively adjustable about the center of the central disk and being in substantially the same 10 plane, a transparent plate covering said disks and having two geometrical axes thereon at right angles to each other, and a scale cooperating with said second disk to indicate the angular position of said line.
- 15 5. A lens marking machine comprising, in combination, a central disk having two geometrical axes thereon at right angles to each other and also having thereon a decentering scale at one side of one of said 20 axes, a second disk of substantially greater diameter than the first disk and having a line located diametrically thereon to designate an axis, said disks being relatively adjustable about the center of the central disk 25 and being in substantially the same plane, a transparent plate covering said disks and having two geometrical axes thereon at right angles to each other, and a scale cooperating with said second disk to indicate the angular position of said line.
- 30 6. A lens marking machine comprising, in combination, a central disk having a scale thereon, a second disk adjustable about the center of said central disk and having means thereon to designate an axis, a transparent 35 plate covering said disks and having two geometrical axes thereon at right angles to each other, means for adjusting said disks about a common axis, means supporting said plate substantially in contact with said 40 disks, and a scale cooperating with said second disk to indicate its angular position.
7. A lens marking machine comprising, in combination, a central disk having a decentering scale thereon, an annular disk encircling said central disk and having a line extending diametrically thereacross, both of said disks being adjustable about the center of the central disk, a transparent plate covering said disks and having two geometrical 45 axes thereon at right angles to each other, and a scale cooperating with said annular disk to indicate the angular position of said line.
8. A lens marking machine comprising, in combination, a central disk having a decentering scale thereon, an annular disk encircling said central disk and having a line extending diametrically thereacross, a pinion 50 fast with said central disk, an annular gear 55 fast with said annular disk, gears meshing, respectively, with said pinion and annular gear for adjusting said disks, a transparent plate covering said disks and having two geometrical axes thereon at right angles to each other, and a stationary scale encircling 60 said annular disk and graduated in degrees.

ALBERT E. COVELLE.
